UNITED STATES PATENT OFFICE.

JOHN MAGUIRE AND WILLIAM A. ALEXANDER, OF MOBILE, ALABAMA.

DREDGING-MACHINE.

SPECIFICATION forming part of Letters Patent No. 224,197, dated February 3, 1880.

Application filed June 25, 1879.

To all whom it may concern:

Be it known that we, JOHN MAGUIRE and WILLIAM A. ALEXANDER, of Mobile, in the county of Mobile and State of Alabama, have invented a new and Improved Dredging Apparatus, of which the following is a specification.

Our improvements relate to vessels and apparatus for river and harbor dredging wherein 10 pumps are made use of for elevating the material from the bottom. We make use of a vessel of suitable dimensions, formed with a central well and water-ballast compartments, whereby the vessel may be sunk to the bottom. 15 The vessel is also fitted with pumping apparatus, whereby the water in the space inclosed by the well is first to be pumped out, and the mud, sand, &c., of the bottom then pumped out to the desired depth. Within the well of 20 the vessel is a frame fitted for being raised and lowered, and carrying discharge-nozzles of a second pumping apparatus, whereby streams of water are discharged for agitating the mud, &c., and rendering it semi-liquid, so that it 25 may be pumped out. These discharge-nozzles are fitted upon carriers that are movable upon slideways, whereby all portions of the inclosed bottom may be subjected to the action of the water.

30 The invention consists in the combination, with the discharge-pumps, of the force-pumps and nozzles, and certain details of construction and combination, whereby the work of dredging in deep and shallow water is expeditiously accomplished, all of which will be described 35 in connection with the accompanying drawings, wherein—

Figure 1 is a plan view of a vessel and apparatus constructed in accordance with our 40 invention. Fig. 2 is a vertical cross-section of the same.

Similar letters of reference indicate corresponding parts.

The apparatus shown is more especially 45 adapted for operations in shallow water and in comparatively unexposed situations.

Referring to Figs. 1 and 2, A is a vessel of suitable dimensions, formed with a central well, a, and with water-ballast compartments 50 b at the sides and ends. Around the bottom of the vessel, at the outside, is a downwardly-

projecting rim, c, of boiler-iron, strengthened by braces, which rim, when the vessel is sunk, enters the mud or sand and excludes water from the vessel a. Within the well a is fitted 55 a frame or casing, B, preferably constructed of boiler-iron, and adapted for being raised or lowered within the well by chains and gearing in any suitable manner. Between the frame B and the sides of the well a friction-rollers d are 60 fitted.

Within the frame B, near the bottom, a pipe, e, is fitted, which pipe extends lengthwise of the vessel, and is supported by a rod, f, at each end, for the purpose of permitting vertical adjustment of the pipe e. The rods f pass through fixed sockets g, and are fitted at their upper ends each with a nut, g'. In the under side of the pipe e there are nozzles h, and from one end of e a flexible pipe, i, extends to the discharge-pumps k, that are fitted upon the deck of the vessel j. l is the discharge-pipe of the pump k.

Upon the top of frame B, or upon supporting-timbers provided for the purpose, carriers C are fitted, which consist of a frame, m, at 75 each side of the vessel, fitted with flanged supporting-rollers n and connected by a cross-bar, O. At each end of the vessel is a cross-shaft, p, carrying grooved rollers or chain-wheels for endless ropes or chains r, that are attached to 80 the frames m of the carriers, so that by revolution of shafts p the carriers C are caused to travel lengthwise of the vessel A in either direction, as desired.

To the cross-bar O of each carrier C there 85 are affixed tubular sockets s, through which pass the rigid pipes t. These pipes t are capable of vertical adjustment in sockets s, whereby their lower ends can be brought nearer to or farther from the bottom of the river, and are 90 retained in position within the sockets by set-screws. The pipes are each connected by a flexible pipe, u, with the force-pumps w, and a pipe, v, from the pumps w extends over the side of the vessel into the water, so that water 95 may be pumped up and discharged by the pipes t within the space inclosed by the well a.

In operation, the vessel A is floated to the desired place, and then, by admitting water 100 to the compartments b, it is sunk to the bottom. The pumps w are then operated, and the water within the inclosed space drawn out by

the pipes *e* and *i* and discharged by the pipe *l*. The frame *B* is next lowered within the well to the required position, and the nozzles *h* and pipes *t* adjusted so that their lower ends are near the bottom, and the pumps *w* put in operation to agitate the mud, &c., of the bottom by the water discharged by the pipes *t*, and also to render the same of the proper consistency for being raised by the pumps *k*, which are to be kept in operation at the same time. The material raised by the pumps *k* will be discharged into a scow at the side of the vessel *A*, and the frame will be gradually lowered until the bottom is excavated to the depth desired, after which sufficient of the water-ballast will be pumped out to permit of floating the vessel to another place.

During the dredging operations the carriers *C* are moved upon their supports so as to subject all parts of the inclosed bottom to the action of the water discharged by pipes *t*.

The vessel is to be fitted with engines for driving the pumps and operating the carriers. In some cases the dredging may be accom-

plished by lowering the frame *B* without sinking the vessel.

Having thus described our invention, we claim as new and desire to secure by Letters Patent—

1. In dredging apparatus, the combination, with the vessel *A*, having a well, *a*, and provided with the suction or discharge pump *k* and force-pump *w*, of the adjustable frame or casing *B*, carrying the suction-pipe *e* and discharge pipes or nozzles *t*, that are separately connected with the pumps, substantially as and for the purposes specified.

2. In dredging apparatus, in combination with the vessel *A* and inner movable frame, *B*, the movable carriers *C* and discharge pipes or nozzles *t*, substantially as and for the purposes specified.

JOHN MAGUIRE.

WILLIAM ANTHONY ALEXANDER.
